UNITED STATES PATENT OFFICE.

WALTER E. COFFIN, OF CLEVELAND, OHIO, ASSIGNOR TO THE NATIONAL MALLEABLE CASTINGS COMPANY, OF CLEVELAND, OHIO, A CORPORATION OF OHIO.

DRAFT-GEAR.

1,105,063.

Specification of Letters Patent. Patented July 28, 1914.

Application filed March 24, 1911. Serial No. 616,683.

To all whom it may concern:

Be it known that I, WALTER E. COFFIN, a citizen of the United States, and a resident of Cleveland, Cuyahoga county, Ohio, have 5 invented a new and useful Improvement in Draft-Gears, of which the following is a full, clear, and exact description, reference being had to the accompanying drawings, forming part of this specification, in which—
10 Figure 1 is a view partially in plan and partially in horizontal section, showing a draft gear embodying my invention applied to a portion of a car; Fig. 2 is a vertical section of the same; Fig. 3 is an enlarged sectional plan view showing the draft rigging; and Fig. 4 is a section on the line IV—IV of Fig. 3.

My invention has relation to draft gears, particularly designed for use on passenger 20 and interurban cars, and has more particular relation to the draft rigging, being designed to provide a simple, novel and effective rigging.

In the drawings, the numeral 2 designates 25 the head of an automatic coupler of well known type having a rearwardly extending shank 3. The forward end of the shank is supported by a stirrup or carry iron 4, with a T portion having a sliding engagement 30 with a slot 5 of a radial segment 6 attached to the car framing. The center of curvature of this segment is coincident with the center of swing of the coupler. The parts thus far described do not constitute any part of the 35 present invention, except in combination.

The draft rigging consists of an outer casing, made up of an upper portion 7^a and a lower portion 7^b, which are adapted to be bolted together and to the under side of the 40 car sills 8 by means of the bolts 7. This casing is shown as having diagonal strengthening ribs 7^c, and its interior is circular in horizontal cross-section. Seated within the cylindrical portion of the casing is an inner casing, which is also composed of an upper portion 9 and a lower portion 9^a held together by means of bolts 10, or other suitable 45 connections. This inner casing contains the draft and buffing springs 11, the front follower 12 and the rear follower 13. The ends of the inner casing are rounded or convexed to conform to the rounded interior of the outside casing within which the inner casing fits and rotates. Projecting from the forward end of the inner casing is a portion 50

14, which incloses the sides of the coupler shank and the rectangular forward end of the tail bolt 15, the forward end of the outer casing being cut away to allow this forward projection of the inner casing to project outwardly therethrough. The tail bolt 15 is secured to the rear end of the coupler shank by means of rivets 16, or in any other suitable manner. The portion of the tail bolt which lies within the shank and through 60 which the rivets pass, is preferably rectangular in cross-section, while the portion passing through the springs and through the front and rear followers is round. The front follower abuts against the rear end of the coupler shank, and the rear follower abuts against a key 17 which passes through the 65 rear end of the tail bolt.

The operation is as follows:—In buffing, 70 the front follower 12 compresses the springs against the rear follower 13, which is held immovable by its engagement with the side walls of the inner casing, which casing in turn bears against the interior walls of the outer casing, and which is rigidly secured to the car framing, as before described. In pulling, the front follower is held immovable, and the springs are compressed by the 75 forward movement of the rear follower, which is pulled forwardly by means of the key 17 attached to the tail bolt.

It will be seen that the coupler head and shank are free to swing by reason of the rotative engagement of the inner casing with the outer casing, and that the draft rigging 80 acts effectively in both pulling and buffing with the coupler shank at different angles to the longitudinal center line of the car body. The inner casing, which contains the springs, is, in effect, a large hollow pivot, which is 85 journaled within the larger outer casing and furnishes a pivotal point for the swinging motion of the coupler shank.

It will be obvious that the construction of 90 the coupler shank and the mode of connecting it with the followers may be widely varied without departing from the spirit and scope of my invention as defined in the appended claims.

What I claim is:—

1. In a draft gear, the combination with a 100 coupler and coupler shank, of a draft rigging comprised of an inner and an outer casing, the inner casing being mounted for pivotal movement within the outer casing 110

and having an extension projecting through the forward wall of the outer casing, said inner casing having a draft rigging spring and followers therein, the two casings being substantially horizontal alinement, substantially as described.

2. A draft rigging comprising an outer sectional casing having concaved inner bearing walls, an inner casing within the outer casing and having convex ends adapted to turn upon the concave bearing walls of the outer casing, the outer casing having an

opening at its forward end, and the inner casing having an extension projecting through said opening, together with spring 15 and follower mechanism within the inner casing; substantially as described.

In testimony whereof, I have hereunto set my hand.

WALTER E. COFFIN.
